(57) **CLAIM**

The ornamental design for a bearing housing, as shown and described.

DESCRIPTION

FIG. 1 is a front perspective view of bearing housing showing a first embodiment of our new design.

FIG. 2 is a top perspective view thereof.

FIG. 3 is an end elevational view thereof, the other end being a mirror image thereof.

FIG. 4 is a front elevational view thereof, the rear being a mirror image thereof.

FIG. 5 is a top plan view thereof.

FIG. 6 is a front perspective view of bearing housing showing a second embodiment of our new design.

FIG. 7 is a top perspective view thereof.

FIG. 8 is an end elevational view thereof, the other end being a mirror image thereof.

FIG. 9 is a front elevational view thereof, the rear being a mirror image thereof.

FIG. 10 is a top plan view thereof.

FIG. 11 is a front perspective view of bearing housing showing a third embodiment of our new design.

FIG. 12 is a top perspective view thereof.

FIG. 13 is an end elevational view thereof, the other end being a mirror image thereof.

FIG. 14 is a front elevational view thereof, the rear being a mirror image thereof; and,

FIG. 15 is a top plan view thereof.
